UNITED STATES PATENT OFFICE.

ROBERT T. JENNEY, OF MONTICELLO, IOWA, ASSIGNOR TO HALL MANUFACTURING CO., OF MONTICELLO, IOWA.

VEHICLE-TONGUE DRAFT APPLIANCE.

1,137,977.

Specification of Letters Patent.

Patented May 4, 1915.

Application filed October 12, 1914. Serial No. 866,313.

To all whom it may concern:

Be it known that I, ROBERT T. JENNEY, a citizen of the United States, and a resident of Monticello, in the county of Jones and 5 State of Iowa, have invented a new and useful Improvement in Vehicle-Tongue Draft Appliances, of which the following is a specification.

My present invention relates to adjustable 10 hounds for steel vehicle-tongues.

Wagon-hounds vary greatly not only as regards their distance of separation but also with respect to their angular relationship or convergency. Therefore, in order that a vehicle tongue of the modern type may be made to fit or conform to practically any of the ordinary types or classes of wagon hounds, it is necessary that it be equipped with tongue-hounds which are not only adjustable bodily with relation to each other, but that either end of either or both be adjustable relatively to the wagon-hounds and to each other.

The primary object of this invention is to 25 generally improve the construction and increase the capacity, utility and efficiency of devices of this character.

More specifically stated: A further object is to provide novel means for carrying out 30 the ends hereinabove described.

A further object is to provide tongue-hounds capable of a greater range of adjustments than any heretofore devised.

A further object is to improve the construction of the corrugated washer whereby 35 flexing of the coacting parts, after adjustment, is prevented.

That the mechanism constituting the means for carrying out the above recited 40 objects be durable, possessed of great strength and resistance, safe in operation, quick and simple of adjustment and secure thereafter, are prime requisites, and to provide such means for carrying out these ends 45 constitutes still another object.

Minor objects will presently appear. Some of these will be obvious and others will be particularly noted.

The invention consists, substantially, in 50 the improvements hereinafter described.

For the purpose of illustrating it I have shown in the accompanying drawings that form thereof which is at present preferred by me, since the same has been found in 55 practice to give gratifying results. How-

ever, I desire it to be distinctly understood that the several instrumentalities of which the invention consists can be variously constructed, arranged and organized, and I by no means contemplate the scope thereof as 60 limited to the particular structure shown and herein described, but consider it as covering all such changes as fairly fall within the scope thereof, considered in its broadest aspect. Moreover, many of the details and 65 combinations illustrated are not essential to the invention, broadly considered.

In said drawings: Figure 1 is a top plan showing my improvements as employed in use. In this view a portion of the tongue, a portion of the upper draft-plate, and a portion of one of the tongue-hounds are broken away. Fig. 2 is a transverse section, taken in the plane of the line 2-2 in Fig. 1; Fig. 3, a similar view, taken in the plane of the 75 line 3-3 in Fig. 1; and Figs. 4 and 5 respectively, a bottom plan and an edge elevation of the improved locking washer.

Referring to each element (and part thereof where necessary) by a distinguishing numeral, uniformly employed, and considering the drawings in detail, 2 designates a tubular steel vehicle-tongue.

3 indicates the lower draft-plate, bent to conform to the cross-sectional curvature of 85 the tongue.

4 designates the upper draft-plate, likewise bent, and having a raised plane portion 5 constituting a seat or bed for the doubletree. The plates 3 and 4 are secured 90 to the tongue in any desired manner, preferably by rivets 6, 7, and their flanges 8, 8 and 9, 9 are spaced apart for a purpose presently described.

10, 10 indicate any suitable means, such 95 as elongated rivets, for securing the plates 3 and 4 to each other. Said plates are provided with registering openings for the reception of bolts 11 and 12, 12.

13, 13, designate connecting or extension 100 arms, each formed practically in the form of a bell-crank. Near its forward end each arm is provided with a longitudinally arranged slot 15, and near its midlength with an arcuate slot 14. The fore portions of 105 these arms have placement between the flanges 8 and 9 of the plates 3 and 4, between which they are adapted to move as hereinafter described, and the bolts 11 and 12 enter the slots 14 and 15 respectively.

16, 16 designate securing nuts.

17, 17 designate wagon-hounds of an ordinary type.

17' is the usual coupling rod by which they are connected to the tongue-hounds 18, and 19 is the securing nut. Each tongue-hound is shown as formed from a piece of U-shaped or channel iron.

20, 20 designate reinforcements fixed to the base of the hounds 18 adjacent the openings for the reception of the coupling rod. At their forward ends the upper and lower webs of the tongue-hounds are provided with apertures for the reception of rivets 21 or the like, by which they are pivotally connected with apertured bosses 22 on the rear ends of the extension arms 13.

23, 23' designate yoke-straps, curved at their midlengths to conform to the curvature of the tongue, to which they are fixed by rivets 24.

25, 25 designate adjusting arms, each provided at its outer end with an apertured boss 26.

27, 27 indicate rivets, one passed through the upper and lower webs of each tongue-hound and through the aperture in the adjacent boss 26.

Each arm 25 has an upper corrugated face 28 and an elongated slot 29.

30, 30 designate locking-washers, each having a corrugated face and each provided with a lug 31 projecting therefrom and adapted to slide in a slot 29, the corrugations 35 engaging those on the coacting arm 25.

32, 32 are bolts passed one through each washer 30 and slot 29, and 33, 33 designate nuts thereon.

35 designates an opening for the hammer 40 or doubletree pin.

The operation: Assume the elements to be in the relative positions shown in Fig. 1. Should it be desired to adjust the rear ends of the tongue-hounds to a pair of wagon 45 hounds having either greater or less convergence than those shown, the operator would loosen the nuts 33 sufficiently to permit the washer to move on the arms 25, whereupon, after the desired adjustments 50 have been made, (the hounds pivoting on the pins 21,) said nuts may be drawn up to lock the parts securely together. The coacting corrugated faces of the washers and arms will of course tend to prevent the former 55 from turning, but should one of the nuts 33 become loose the washer will be positively locked from turning, because of its lug 31 being seated (somewhat snugly) in the slot 29. Now assume it desirable to adjust 60 the front ends of the hounds. The operator will loosen the nuts 16 and move said front ends either inward or outward. The slots of the arms 13 will ride the bolts 11 and 12 and the rear ends of said arms will, by reason 65 of the pivot pins or rivets 21, be thereby

moved laterally, but in such manner that the centers of said pins or rivets are maintained constantly on a line—designated by "A," Fig. 1—perpendicular or at right angles to the longitudinal central line of the 70 tongue, and simultaneously the front portions of said arms will move in a forward or a rearward direction, according as the front ends of the hounds 18 are moved inward or outward, as indicated by the dotted lines 75 in said figure. The main advantage gained by these constructions are that they allow a greater range of adjustment than has heretofore been attained, and the arms prevent the pivotal movement which would result 80 from a fixed arm working on a single bolt, which pivotal motion would have a tendency to throw the tongue hounds forward or back, as the change was made, the result of which would be to cause the coupling pin 17' to 85 bind in the hole in the tongue.

It will be readily seen that when the nuts 33 are loosened the hounds 18 will pivot on the pins 21, and that when the nuts 16 are loosened said hounds will pivot on the pins 27, but that when all of said nuts are drawn 90 taut the structure becomes an extremely rigid and inflexible one.

A tongue-hound made of channel iron, or in U-shape, not only possesses extreme 95 strength and rigidity but is quite economic of manufacture.

Having thus set forth the nature of my invention I claim as new and desire to secure by Letters Patent the following, to-wit:— 100

1. A device of the character described comprising draft means, a pair of tongue-hounds, extension arms having each a pair of slots of which one is arcuate, bolts or the like connecting said arms, through said slots, 105 with said draft means, and means for pivotally connecting said arms each with one of said hounds.

2. In a device of the character described, a tongue, a channel-iron tongue-hound, an extension arm pivoted between its webs, said arm having an arcuate slot, draft means secured to said tongue, and a bolt passed through an aperture in said draft means and seated in said slot, provision being made 115 whereby to so guide the arm that the point at which it is pivoted to the hound will be adjustable in a line perpendicular to the tongue.

3. In a device of the character described, 120 a tongue, means for adjusting a hound relative to the tongue and including a washer provided with a projection and a corrugated face, and corrugated means provided with a slot with which said projection co-operates, 125 whereby said washer is prevented from turning relatively to said slot, and further whereby its corrugations are held always to register with the corrugations of said corrugated means. 130

4. In a device of the character described, a tongue, a tongue-hound, a slotted arm engaged with said hound, connecting means interposed between said tongue and arm, 5 means provided with a projection adapted to seat and move in the slot in said arm, whereby said means is prevented from turning relatively to said arm, and means for securing said arm, connecting means, and the 10 last recited element in fixed relationship.
5. An extension arm for devices of the character described, said arm having an arcuate and a longitudinally arranged slot, draft means with which its forward end is 15 connected, and a tongue-hound with which its rear end is connected.
6. An extension arm for devices of the character described, said arm having an arcuate slot near its midlength, draft means 20 with which its forward end is connected, and a tongue-hound with which its rear end is connected.
7. In a device of the character described, a tongue, a tongue-hound, a draft-yoke secured to said tongue, an arm provided with 25 a slot, intermediate said tongue and hound, a washer having a projection adapted to seat in said slot, and means for locking said arm, washer and yoke together.
8. In a device of the character described, a tongue, spaced draft-plates, a pair of extension arms movably connected with and 30 between said plates, a pair of tongue-hounds, a pair of corrugated and slotted arms pivotally connected with their rear ends, a pair 35 of corrugated washers each provided with a lug, the corrugations of the washers adapted to engage those of said arms and said lugs to engage said slots, connecting means intermediate the tongue and said arms, and bolts for connecting each adjacent corrugated arm washer and said connecting means. 40
9. In a device of the character described, a tongue, a tongue-hound, an extension arm connected with said hound and provided 45 with an arcuate slot, draft-means secured to said tongue, means for engaging said draft-means with said slot, and means coöperating with said slot to so guide the arm that the point at which it is connected to the hound 50 will be adjustable in a line perpendicular to the tongue.
10. In a device of the character described, a tongue, a tongue-hound, an extension arm connected with said hound and provided 55 with an arcuate slot, draft-means secured to said tongue, and means coöperating with said slot and draft-means whereby to so guide the arm that the point at which it is connected with said hound will be adjustable 60 in a line perpendicular with the tongue.
- In testimony that I claim the foregoing as my sole invention I hereto subscribe my name, in presence of two witnesses, at Monticello, Iowa, this 6th day of October, 1914. 65

ROBERT T. JENNEY.
